UNITED STATES PATENT OFFICE.

HERBERT R. MCCLINTOCK, OF EL PASO, TEXAS.

CIGAR OR CIGARETTE HOLDER.

1,366,291.

Specification of Letters Patent. Patented May 14, 1918.

Application filed July 20, 1917. Serial No. 161,884.

To all whom it may concern:

Be it known that I, HERBERT R. MCCLINTOCK, a citizen of the United States, residing at El Paso, in the county of El Paso and 5 State of Texas, have invented a new and useful Cigar or Cigarette Holder, of which the following is a specification.

The invention relates to a cigar or cigarette holder, and more especially to the class 10 of stub ejecting cigar or cigarette holders or mouth pieces.

The primary object of the invention is the provision of a holder or mouth piece of this character, wherein the stub of a cigar or 15 cigarette can be readily and easily ejected therefrom to avoid the choking of said holder or mouth piece, and also eliminating the trouble of removing the stub of the cigar or cigarette from said holder or mouth 20 piece by the use of any handy instrument, as is usually required.

Another object of the invention is the provision of a holder or mouth piece of this character, wherein the ejecting device can be 25 readily removed from the stock of said holder or mouth piece, so that either the latter or the device can be readily cleaned with despatch, whereby the said holder or mouth piece will be rendered sanitary, the 30 device being of a peculiar construction to avoid the accumulation of nicotin or tobacco within the holder or mouth piece, and thus eliminating any possibility of the latter becoming foul or impractical during continued 35 use thereof.

A further object of the invention is the provision of a holder or mouth piece of this character, which possesses simplicity in construction, is thoroughly reliable and efficient 40 in its purpose, easily operated to eject a cigar or cigarette therefrom without excessive trouble on the part of the user, and also one which is inexpensive in manufacture.

With these and other objects in view, the 45 invention consists in the features of construction, combination and arrangement of parts, as will be hereinafter fully described, illustrated in the accompanying drawing, and pointed out in the claims hereunto appended.

In the accompanying drawing:

Figure 1 is a side elevation of a holder or

mouth piece constructed in accordance with the invention, showing a cigarette held therein.

Fig. 2 is an enlarged horizontal sectional view, taken longitudinally through the holder or mouth piece, and showing by full lines the normal position of the ejecting device and by dotted lines the adjusted position for the removal of a cigar or cigarette.

Fig. 3 is an enlarged sectional view on the line 3-3 of Fig. 1, looking in the direction of the arrow.

Fig. 4 is a fragmentary top plan view of the holder or mouth piece.

Fig. 5 is a perspective view of the ejecting device removed with the actuating pin or lug detached therefrom.

Similar reference characters indicate like 70 parts throughout all of the views in the drawing.

Referring to the drawing in detail, A designates generally the holder or mouth piece, which is preferably of substantially 75 oval formation, in cross section throughout its length, formed with a cigarette or cigar receiving end 10, having a socket 11 for accommodating the cigar or cigarette, while the opposite end forms a mouth tip 12, 80 through which opens the central draft bore 13 extending in the direction of and opening into the socket 11 as usual, the inner end of the socket 11 being tapered toward the tip end so that the stub of the cigarette or 85 cigar will be firmly held in the socket 11 when forced thereto to be carried by the holder or mouth piece for the smoking thereof.

The holder or mouth piece A is made from 90 any suitable stock preferably amber, although it may be made from a composition or any other suitable material, and formed in the stock at one side of the central bore 13 therein is a guide passage 14, which extends substantially parallel with the bore and at one end opens into the socket 11, while intersecting a portion of the passage 14 near the other end is an elongated slot 15, which opens through the outer face of the stock and this passage 14 and slot 15 are provided for accommodating an ejecting device, which comprises a rod 16, slidably fitted within the passage 14 and having its

outer end portion bent at right angles to form an ejecting prong 17, which extends into the socket 11 crosswise thereof to engage with the butt end of the cigarette or cigar when held in the holder or mouth piece, so that on movement of the rod 16 in one direction, the butt end of said cigar or cigarette will be ejected from the socket 11, when it has been smoked and the greater portion thereof consumed.

The opposite or inner end portion of the rod 16 carries a finger stub or pin 18, which is formed with a reduced threaded portion 19 adapted to be detachably tapped into the rod 16 near the inner end thereof, and this pin or stub 18 works in the slot 15, which is of a width to frictionally engage therewith to avoid the free sliding of the pin or stub therein. The stub or pin 18 projects outwardly from the slot 15 and is formed with a head 20 to permit the convenient engagement thereof by the finger of the user of the cigarette or holder, so that the ejecting device can be readily manipulated in the direction required for ejecting the stub of a cigarette or cigar from within the socket 11 in the holder or mouth piece.

Normally, the rod 16 of the ejecting device is moved inwardly to the position shown by full lines in Fig. 2 of the drawing, so that the stub end of a cigarette or cigar can be readily inserted in the socket 11 for the smoking thereof. Now, when it is desired to eject the stub of the cigarette or cigar, the rod 16 is shifted, so that the ejecting device will assume the position shown by dotted lines in Fig. 2 of the drawing, and on this outward movement of said device, the prong 17 will act upon the stub of the cigar or cigarette, forcing it from the socket 14 within the stock of the holder or mouth piece, and thereby ejecting said stub therefrom.

The guide passage 14 corresponds with the cross sectional diameter of the rod 16, so that the latter will snugly fit within the passage 14 for slight frictional engagement between the wall of the passage and said rod, thereby preventing the loose working of the rod in the passage or the free sliding of the ejecting device within the stock of the holder or mouth piece.

The ejecting device can be readily moved by hand to its normal position or to the position for ejecting the stub of the cigar or cigarette from the holder or mouth piece in a manner as hereinbefore set forth.

The stop or pin 18 can be readily detached from the rod 16, so that the same can be drawn out of the passage 14 through the socket 11 for the removal of the ejecting device from the holder or mouth piece, so that both the latter and the ejecting device can be readily cleaned for sanitary purposes, yet it is to be understood that when the eject-

ing device is within the holder or mouth piece, the same can be cleansed when the occasion requires.

On the rod 16 next to the ejecting prong 17 is a cone-shaped valve or stopper 21 which is adapted to engage in a seat 22 correspondingly shaped thereto and formed at the outer end of the passage 14 so that when the rod is retracted within said passage, the valve or stopper 21 closes the passage 14 to completely close the same to avoid affecting the draft through the smoke bore 13 when the holder is in use for smoking the cigar or cigarette.

It is to be understood that the holder or mouth piece in lieu of oval formation in cross section throughout its length may be of any desired shape or configuration.

From the foregoing, it is thought that the construction and manner of operation of the invention will be clearly understood, and, therefore, a more extended explanation has been omitted.

What is claimed is:—

1. A holder or mouth piece of the character described comprising a stock having a socket opening through one end and also having a bore leading from said socket through the other end of the stock, said stock further having a communicating passage and slot, the passage being substantially parallel with the bore and opening into the socket, while the slot opens through one side of the stock, a rod slidably in the passage and having an outer end bent at right angles and extending into the socket, and a headed pin passed through the slot and having a threaded end detachably engaged in the inner end of the rod.

2. A holder or mouth piece of the character described comprising a stock having a socket opening through one end and also having a bore leading from said socket through the other end of the stock, said stock further having a communicating passage and slot, the passage opening into the socket and the slot opening through one side of the stock, an ejecting member slidably fitted in the passage, manually operated means working in the slot and engaged with the ejecting member, and a closure member on the ejecting member for engagement in the outer end of the passage to completely close communication between the socket and said passage when the ejecting member is in normal position.

3. A holder or mouth piece of the character described, comprising a stock having a socket in one end and also having a bore leading from said socket through the other end of the stock, and an ejector rod slidably fitted within the stock and having an ejector prong projected into the socket, a valve on said rod to engage in the stock about the rod

when in normal retracted position for preventing air leakage around the same.

4. A holder or mouth piece of the character described, comprising a stock having a socket in one end and also having a bore leading from said socket through the other end of the stock, an ejector rod slidably fitted in the stock and having an ejecting prong projected into the socket, a valve on the rod for preventing air leakage about the rod when said rod is in normal retarded po-

sition, and manually operated means projected outside of the stock for actuating the rod.

In testimony that I claim the foregoing as 15 my own, I have hereto affixed my signature in the presence of two witnesses.

HERBERT R. McCLINTOCK.
